Specification of Letters Patent. Patented Nov. 7, 1916.

Application filed September 30, 1915. Serial No. 53,263.

To all whom it may concern:

Be it known that we, AXEL VALDEMAR CLORIUS and ODIN THORVALD CLORIUS, subjects of the King of Denmark, residing at 5 Frederiksberg, near Copenhagen, Denmark, and Hellerup, near Copenhagen, Denmark, respectively, have invented a new and useful Improvement in Games of Skill; and we do hereby declare the following to be a 10 full, clear, and exact description of the same.

This invention relates to improvements in amusement devices in which a number of units such as carriages, dolls, horses or the 15 like are adapted to be propelled along a race course by the manipulation of a corresponding number of hand wheels, each operator or player striving to be the first to bring his unit to the winning post and thereby win 20 the race.

The chief object of the invention is to render such devices more attractive and entertaining by enabling the units to get out of the control of the operators under certain 25 conditions and remain stationary or actually turn and move in a direction away from the winning post.

According to this invention the units are adapted to be freed or disconnected from 30 their corresponding hand wheels when the speed of rotation of the latter exceeds a predetermined value, so that they remain stationary or actually turn and move in an opposite direction out of the control of the operators or players. The desired disconnection of the hand wheels and units may be obtained through the intervention of suitable clutching devices, and the turning and retrograde movements of the units may be 35 attained by falling weights or other suitable means. When the race has been won by one of the units, the attendant is able to disconnect all the units from the hand wheels, so that they may automatically return to the 40 starting point. In a similar manner when a race is to be started, the attendant can connect the units to the corresponding hand wheels.

For the sake of clearness, the word unit 50 will be hereinafter employed in the specification to designate the member which trav-

erses the course but it will be understood that such term is intended to cover a carriage, horse, doll or any other figure that may be used with the device.

In order that the said invention may be clearly understood and readily carried into effect the same will now be described more fully with reference to the embodiment illustrated in the accompanying drawings, 55 in which:—

Figure 1 is a diagrammatic representation of a single unit and its connections: Fig. 2 is a sectional elevation of one form of speed limiting clutch for use with the invention. 65 Fig. 3 is a sectional front elevation taken on line 3—3 in Fig. 4 of a form of the improved device provided with a race course for four units. Fig. 4 is a sectional end elevation taken on line 4—4 of Fig. 3. Fig. 5 70 is a sectional plan taken on line 5—5 of Fig. 3. Fig. 6 is an underside view of one of the units showing the method of connecting the actuating cords thereto. Figs. 7, 8 and 9 are elevations in part section showing 75 a clutching device set in three different positions.

Referring to Fig. 1, *a* is the unit which is formed as a horse and rider, and mounted upon a spindle *e* which is rotatably mounted in a slide *b*, capable of moving along the race course *b'*. The lower end of the spindle *e* is provided with a pulley *e* which is suitably connected to strings or cords *c*, *c'* which are adapted to move the slide in opposite 85 directions along the course. These cords are connected to a common point or slot on the pulley *e*, in such a manner that owing to the friction of the slide on the course *b'* the unit will be turned to face the direction 90 in which the pull is exerted. As shown in Fig. 6 the pull is exerted on the cord *c*. The cord *c'* passes over a pulley *k* and is provided at its lower end with a weight *l* which tends to return the unit to the right hand 95 end or starting point of the course. The other cord *c* passes over guide pulleys *f*, *f* and has its extremity connected to a winding device or drum *g* which is adapted to be operatively connected with the hand wheel 100 6 through the intervention of the clutching device *o*, shown in Fig. 2. The drum *g* is

loosely mounted on a shaft n which is arranged in alignment with a shaft m operatively connected through suitable bevel or other gearing to a shaft s , Fig. 4, which carries the hand wheel 6.

As clearly shown in Fig. 5, the four hand wheels 6 are each provided with a corresponding drum g , which is operatively connected therewith through the intervention of a clutching device which will be hereinafter described. Adjacent to the drum g on the shaft n is loosely mounted a sheave s which is driven at a uniform speed by a motor 2 through a rope or belt drive, g' .
 15 The drum g is provided with a spring controlled pin r , the tapered head of which is adapted to project and engage with a radial pin p provided on the shaft n . When these two parts are in engagement the shaft n
 20 will serve to impart rotary movement to the drum g . Owing to the conical formation of the head of the pin r the radial pin p on the shaft will tend to displace the drum in the right hand direction along the shaft n but
 25 this movement of the drum is prevented owing to the boss thereof abutting against the boss of the sheave s . The right hand portion of the boss of the sheave s is provided with an internal thread t and a cor-
 30 responding male thread u is formed on the shaft n adjacent thereto. The arrangement is such that when the shaft n is at rest, or rotating at a speed which is equal to that of the sheave s , there will be no tendency for
 35 the thread u to engage with the internal thread t . Should, however, the speed of the shaft n exceed that of the sheave s , the thread u will pass into engagement with the thread t and thereby displace or draw the
 40 sheave in the right hand direction along the shaft against the action of the spring 7. This movement of the sheave will permit of the drum g moving in the same direction to allow the pin r thereof to disengage from
 45 the radial pin p on the shaft n . It will be seen, therefore, that this will permit of the drum g being released, and owing to the action of the weight 1, it will be turned in the opposite direction and the unit a will
 50 be returned or moved toward the starting point of the track.

As previously mentioned the direction in which the unit faces is dependent on the direction in which the pull is applied there-
 55 to, and consequently assuming the cord c was imparting movement to the slide and unit toward the left hand side of the course prior to the disconnection of the pulley g from the shaft n immediately such discon-
 60 nection takes place, pull will be imparted to the unit and slide through the string c' and cause the same to turn and face the opposite direction and return toward the starting point. The spring 7 may be arranged be-
 65 tween two collars n' , n^2 mounted on the

shaft n , the collar n^2 being loosely mounted or splined thereon while the collar n' is rigidly secured thereto. The spring 7 always tends to disengage the thread u from the internal thread t of the sheave, and serves to 70 disengage or reset these parts when the proper conditions obtain.

The adjacent ends of the aligned shafts n and m , are embraced by a coupling sleeve o which is adapted to be displaced by a cam p' carried by a shaft P^0 arranged above the sleeve and mounted in suitable bearings P^4 . A suitable controlling handle or lever P^2 , is connected to the cam p' and said handle is adapted to be moved to assume the three positions shown in Fig. 2. The shaft n is provided with a radial pin n^3 which is adapted to engage with a slot or depression formed in the sleeve o , while the shaft m is provided with similar pin m' which is always in operative engagement with a slot 80 m^2 in the sleeve o .

When the handle P^2 is in the position shown in Fig. 7, the spring m^2 serves to maintain the sleeve o so that the pin m' of the shaft m is at the right hand end of the slot m^2 in the sleeve and the depression n^4 therein in engagement with the pin n^3 of the shaft n . Consequently, it will be readily seen that the shaft m will be coupled to the shaft n so that the shaft m actuates the shaft n according to the revolutions imparted thereto by the hand wheel 6 and intermediate gearing. The cam p' is connected to the shaft P^0 by means of the radial pin P^4 rigidly secured to said shaft and projecting into a radial opening P^5 formed in the cam. The outer end of the pin P^4 is provided with a collar P^6 which is acted upon by a spring P^7 so as to draw the pin outwardly and press the shaft P^0 against the portion of the aperture P^8 in the cam adjacent to the mouth of the radial opening P^5 . As shown in Fig. 7 the aperture P^8 in the cam is larger than the shaft P^0 so that relative lateral movement can take place between the cam and shaft when the action of the spring P^7 is overcome. Assuming the handle P^2 is turned toward the position shown in Fig. 8, the shoulder P^9 of the cam will engage with the collar m^4 of the sleeve o and impart a sliding movement thereto in the right hand direction to uncouple the shafts m and n and at the same time the point P^3 of the cam will gradually engage with the sleeve and as the pressure between the point P^3 and the sleeve increases, the cam p' will be laterally displaced with respect to the cam shaft P^0 against the action of the spring P^7 . The pressure applied to the sleeve o is thus graduated and becomes a maximum when the handle assumes the intermediate position shown in Fig. 8. When the handle is in this position the pressure applied to the sleeve is sufficient to bind the shaft n to prevent the 100 105 110 115 120 125 130

same running back under the influence of the weight l so that the relative positions of the units at that instant may be readily ascertained.

5 The shaft p^0 is provided with a number of cams p' corresponding to the number of drums g provided on the device, and it will be understood that the movements of the shaft p^0 serve to control all of the drums 10 and their corresponding units. The attendant who controls the starting and stopping of the race operates the lever p^2 and, as previously mentioned, moves the same into the intermediate position when one of the units 15 has reached the winning post on the course. This movement of the handle p^2 serves to disconnect all the units from their hand wheels, 6, and serves to retain the units in their final positions so that the various players 20 may ascertain the position of their units at the end of the race. After the necessary particulars have been obtained regarding the result of the race, the lever p^2 is turned to the left hand position shown in Fig. 9, so 25 that the surface of the cam again comes into operation to maintain the sleeve o in the right hand displaced position and thereby permanently disconnect the shafts m and n , and permit the counterweights to return the 30 units to the starting position.

Referring to Figs. 3 to 5, four hand wheels 6 are provided and they are mounted on a table 10 and connected to four winding drums g , through the intervention of the 35 aforesaid speed controlling clutches. The table 10 is arranged at the extremity of a platform 11, Fig. 4, which projects outwardly from the main structure 12 of the device and the arrangement is such that said platform 40 forms a passageway between the hand wheels and the units. Each hand wheel is constructed and connected in a similar manner and each drum g is operatively connected by a suitable string or cord c to its corresponding 45 unit as shown in Fig. 1. The sheaves s which are arranged adjacent to the aforesaid drums g are driven by means of a motor 2 through a suitable rope or belt drive which passes over said sheaves and intermediate 50 jockey pulleys 3, which serve to maintain the desired tension thereon. When a race is to be started all the units are situated at the right end of the course and the attendant or starter throws all of the clutches o 55 into engagement by turning the handle p^2 into the position shown in full lines in Fig. 2. The players then turn their hand wheels 6 so as to wind up the cords c on to the drums g and the units are consequently drawn toward the left hand end of the course, the necessary movement being transmitted to the drums g through the conical pins r thereof and the radial pins p on the shafts n . Owing to the conical formation of the pins r 65 the pins p on the shafts n will tend to force

the drums g toward the right, Fig. 2, against the pressure of the comparatively light springs 7.

Should one or more of the players turn the shafts n at a greater speed than that at which the sheaves s are being driven, the threads u on the shafts n will enter and engage the internal threads in the hubs of the sheaves and thereby permit of the disengagement of the corresponding drums g 75 from the radial pins p . When this occurs the weights l will as previously described, turn the corresponding units to face the opposite direction and keep the same stationary or actually move them toward the starting 80 point. If a player, when this occurs, stops rotating his hand wheel or reduces the speed at which he is turning the same, the rotating sheave s will automatically unscrew its hub from the thread u and the two pins p 85 and r , will again be engaged so that motion in the proper direction can be transmitted to the unit through cord c . This will also cause the unit to be turned to face the winning post. As the hubs of the winding drums g 90 are normally in abutment with the hubs of the sheaves s and the latter are rotated continuously by the motor 2, the slight frictional contact between the hubs will tend to cause the winding drums g to turn in the 95 same direction as the sheaves s . In this manner the cords c connecting the winding drums with the units will be maintained under tension so that motion will be imparted to the latter immediately the necessary 100 clutching operation is effected by the attendant and the handles 6 are turned by the players.

While only one form of the present invention is clearly shown and described above, 105 it will be understood that the above description and the accompanying illustrations are not intended as a limitation, but that applicants reserve the right to make whatever changes and alterations, either in the various 110 elements or combination of elements which comprise the present invention, as may come within the scope of the appended claims.

We claim—

1. In an amusement device, the combination of a unit, a course along which said unit is adapted to travel, a hand operated member for displacing said unit along the course and means for releasing the operative connection between said hand operated member and unit when the speed of the hand operated member exceeds a predetermined value.
2. In an amusement device, the combination of a unit, a course along which said unit is adapted to travel, a hand operated member for displacing said unit along the course, means for releasing the operative connection between said hand operated member and the unit when the speed of the hand operated member exceeds a predetermined value.

- member exceeds a predetermined value and means for imparting a turning movement to said unit so that it faces the opposite direction and remains at rest when the operative connection between the hand operated member and unit is released. 5
3. In an amusement device, the combination of a number of units, a course along which said units are adapted to travel, hand operated members for displacing said units along the course, and means for releasing the operative connection between said hand operated members and units when the speed of the hand operated members exceeds a predetermined value. 10
4. In an amusement device, the combination of a number of units, a course along which said units are adapted to travel, hand operated members for displacing said units along the course, means for releasing the operative connection between said hand operated members and units when the speed of the hand operated members exceeds a predetermined value and means for imparting a turning movement to said units so that they face the opposite direction and remain at rest when the operative connection between the hand wheels and units is released. 15
5. In an amusement device, the combination of a number of units, a course along which said units are adapted to travel, hand wheels for displacing said units along the course, means for releasing the operative connection between said hand wheels and units when the speed of the hand wheels exceeds a predetermined value, and means for imparting a turning and retrograde movement to said units when the operative connection between the hand wheels and units is released. 20
6. In an amusement device, the combination of a race course, a plurality of units adapted to move along said course, a plurality of slides on which said units are mounted, so as to be capable of angular displacement, hand wheels for displacing said units along the course, clutches arranged between said hand wheels and units for releasing the operative connection between said parts when the speed of the hand wheels exceeds a predetermined limit and means for imparting a turning and retrograde movement to said units when the operative connection between the hand wheels and units is released. 25
7. In an amusement device the combination with a race course of a plurality of units adapted to traverse said course, a plurality of falling weights, means for connecting said weights to the units, a plurality of winding drums, means for operatively connecting said winding drums to said units, a plurality of hand wheels, clutches for operatively connecting said hand wheels to the winding drums, and means for automatically controlling the operative connection between the hand wheels and winding drums so as to release the connection when the speed of the hand wheels exceeds a predetermined value and remake the same when the speed is again brought within the limit speed. 70
8. In an amusement device, the combination with a race course of a plurality of units adapted to traverse said course, a plurality of falling weights, means for connecting said weights to the units so that they tend to maintain the units at the starting end of the course, a plurality of winding drums for moving the units to the opposite end of the course, cords for operatively connecting said winding drums to the units, a plurality of hand wheels, clutches for operatively connecting said hand wheels to the winding drums, continuously rotating members adapted to automatically release said clutches when the speed of the hand wheels exceeds a predetermined speed dependent on the speed of the said continuously rotating members. 75
9. In an amusement device, the combination with a race course of a unit adapted to travel said course, a falling weight, means for connecting said weight to the unit so that it tends to maintain the unit at the starting end of the course, a winding drum for moving the unit to the opposite end of the course, a cord for operatively connecting said winding drum to the unit, a hand wheel, a clutch for operatively connecting said hand wheel to the winding drum, and a continuously rotating member adapted to automatically release said clutch when the speed of the hand wheels exceeds a predetermined speed dependent on the speed of the said continuously rotating member. 80
10. In an amusement device the combination with a race course of a slide adapted to be drawn along said course, a spindle journaled in said slide, a pulley fixed on the said spindle, a cord wound on and attached at one end to the circumference of the said pulley, a winding drum connected to the other end of said cord, a hand operated member, a clutch for operatively connecting the hand operated member with the said drum, a sheaf driven at a constant speed and adapted to release the said clutch when the speed of the said hand operated member exceeds a predetermined speed dependent on the speed of the said constantly driven member, a falling weight, a cord connecting said weight to the pulley of the spindle of the slide, and adapted to turn said spindle through half a revolution when the said clutch is released. 85
11. In an amusement device the combination with a race course of a number of slides, adapted to be drawn along said course, spindles journaled in said slides, pulleys 90
- 120
- 115
- 125
- 130

- fixed on said spindles, cords wound on and attached at one end to circumferences of said pulleys, winding drums connected to other ends of said cords, hand operated members, 5 clutches for operatively connecting said hand operated members with said drums, sheaves driven at a constant speed and adapted to release said clutches when the speed of the hand operated members exceeds a predetermined speed dependent on the speed of said constantly driven members, falling weights, cords connecting said weights to the pulleys of the spindles of the slides and adapted to turn said spindles 10 through half a revolution when said clutches are released.
12. In an amusement device the combination with a race course of a hand operated shaft, a clutch for connecting said shaft with the unit, a sheaf adapted to freely revolve on said shaft, a motor for driving said sheaf at a constant speed, a thread in the hub of the said sheaf and a thread on the hand operated shaft adapted to engage the thread 15 in the hub of the sheaf when the speed of the said shaft exceeds that of the sheaf, so as to disengage the said clutch.
13. In an amusement device the combination with a race course of a number of units, 20 hand operated shafts, clutches for connecting said shafts with the units, sheaves adapted to freely revolve on said shafts, motors for driving said sheaves at a constant speed, threads in the hubs of said 25 sheaves and threads on the hand operated shafts adapted to engage the threads in the hubs of the sheaves when the speed of the said shafts exceeds that of the sheaves, so as to disengage said clutches.
14. In an amusement device, the combination with a race course of a number of units adapted to traverse said course, a plurality of hand operated shafts, a plurality of winding drums mounted on said shafts, a plurality of clutches for operatively connecting said drums to the shafts, a plurality of continuously rotating sheaves arranged adjacent said drums and in abutment therewith, internal threads in the hubs of said sheaves, 30 threads on the shafts adapted to engage with said internal threads when the speed of the shafts exceeds the speed of the sheaves, so as to withdraw said sheaves from abutment with the winding drums and permit of the same being disconnected with the driving shafts.
15. In an amusement device, the combination with a race course of a plurality of slides adapted to move along said course, angularly displaceable spindles carried by said slides, units mounted on said spindles, pulleys carried by the lower ends of said spindles, a plurality of falling weights, cords for connecting said weights to the pulleys, a 35 plurality of hand wheels, a plurality of driv-
- ing shafts, means for operatively connecting said hand wheels to the driving shafts, a plurality of driven shafts coaxial with said driving shafts, a plurality of clutches for connecting and disconnecting said coaxial shafts, a plurality of winding drums mounted on said driven shafts, cords for enabling said winding drums to displace the slides along the course, and incidentally head the same in the right direction, means for 40 clutching said drums to the driven shafts, a plurality of members rotating at constant speed adjacent to said drums and tending to turn the latter in the same direction, internal threads in the hubs of said sheaves, 45 threads on the driven shafts which are adapted to enter the threads in the hubs of the sheaves when the speed of the driven shafts exceeds that of the sheaves so as to laterally displace said sheaves and allow of the winding drums being disconnected from 50 the driven shafts.
16. In an amusement device, the combination of a main structure including a course, a plurality of units adapted to travel over said course, a table arranged at a distance from said course, hand operated means upon said table for controlling the travel of said units, a platform between said table and said units, and means extending beneath said platform and connecting said hand operated means with said units.
17. In an amusement device, the combination of a main structure including a course, a plurality of units adapted to travel over said course, a table arranged at a distance from said course, hand operated means arranged on said table, shafts extending angularly from said table and each connected with one of said hand operated means, power transmitting means extending from each of said shafts, and means disposed in said main structure and connected with said units and also connected with said power transmitting mechanism, whereby 100 operation of said hand operated means controls the travel of said units.
18. In an amusement device, the combination of a plurality of units, a course along which said units are adapted to travel, a plurality of hand operated means remote from said course and disposed in alignment parallel thereto, means providing a passage way between said hand operated means and the course, and means for operatively connecting said hand operated means with the units for displacing same along the course.
19. In an amusement device, the combination of a plurality of units, a course along which said units are adapted to travel, a plurality of hand operated means for displacing said units, and a manually-operated member for simultaneously clutching all of said hand operated means with said units.
20. In an amusement device, the combina-

- tion of a plurality of units, a course along which said units are adapted to travel, a plurality of hand-operated means for displacing said units, and a manually operated member for simultaneously unclutching all of said hand-operated means from said units. 70
21. In an amusement device, the combination of a plurality of units, a course along which said units are adapted to travel, a plurality of hand-operated means for displacing said units, and a hand operated member for simultaneously connecting all of said hand operated means with the units, and for simultaneously disconnecting all of said hand operated means from the units. 75
22. In an amusement device, the combination of a plurality of units, a course along which said units are adapted to travel, a plurality of hand-operated means for displacing said units, a hand operated member for simultaneously disconnecting said hand operated means from the units, and automatic means for imparting retrograde movement to said units. 80
23. In an amusement device, the combination of a main structure including a course, a plurality of units adapted to travel over said course, a table arranged at a distance from said course, hand operated means upon said table for controlling the travel of said units, a platform between said table and said units, normally disestablished means extending beneath said platform for connecting said hand wheels with said units, and a manually operated member in proximity with said table for establishing said connecting means between the units and the hand operated means. 85
24. In an amusement device, the combination of a unit, a course along which said unit is adapted to travel, hand operated means for displacing said unit, and means operable at a predetermined speed of operation of the said hand operated member for automatically controlling the speed of travel of the aforesaid unit. 90
25. In an amusement device, the combination of a unit, a course along which said unit is adapted to travel, means for displacing said unit, and means under control of the said displacing means for automatically reversing the direction of movement of the said unit. 95
26. In an amusement device, the combination of a unit, a course along which said unit is adapted to travel, hand operated means for displacing said unit and means under control of the said hand operated member and operable during the travel of said unit for automatically reversing the direction of movement of the said unit. 100
27. In an amusement device, the combination of a unit normally positioned to face in a predetermined direction, a course along which said unit is adapted to travel, means for displacing said unit, and means under control of the said displacing means for automatically reversing the direction of movement of the said unit. 105
28. In an amusement device, the combination of a unit normally positioned to face in a predetermined direction, a course along which said unit is adapted to travel, means for displacing said unit, and means under control of the said member for automatically positioning said unit to face in a different direction. 110
29. In a device of the character described, a clutching device comprising two rotating members and means for automatically imparting a longitudinal unclutching or clutching movement to one of said members when the speed of the other member exceeds or is lower than a predetermined value. 115
30. In a device of the character described, a clutching device comprising a member rotating at constant speed, a member rotating at variable speed and means controlled by the variable speed member for imparting a longitudinal unclutching or clutching movement to the constant speed member when the speed of the variable speed member exceeds or is lower than a predetermined value. 120
31. In an amusement device, the combination of a unit, a course along which said unit is adapted to travel, a hand operated member for displacing said unit, and means operable at a predetermined speed of operation of the hand operated member for automatically controlling the direction of movement of said unit. 125
32. In an amusement device, the combination of a unit, normally positioned to face in a predetermined direction, a course along which said unit is adapted to travel, a hand operated member for displacing said unit, and means operable at a predetermined speed of operation of said hand operated member for automatically positioning said unit to face in a different direction. 130
33. In an amusement device, the combination of a plurality of units normally positioned to face in a predetermined direction, a course along which said units are adapted to travel in a direction which they face, a plurality of hand operated members, each of said members displacing one of said units, and means under control of each of said members and operable at a predetermined speed of operation of said hand operated members for automatically controlling the speed of travel of said units, the direction of movement of said units and the direction in which said units are positioned. 135
34. In an amusement device, the combination of a plurality of units, a course along which said units are adapted to travel, a

plurality of hand operated means, means connected with said units to cause said units to travel along the course at a speed which is determined by the speed of operation of 5 the said hand operated means, and automatic means for causing a return movement of any one of said units during the operation of the hand operated means.

35. In an amusement device, the combination of a plurality of units, a course along which said units are adapted to travel, a plurality of hand operated means, means connected with said units to cause the same to travel along the course at a speed which is determined by the speed of operation of 10 said hand operated means, and automatic means for causing any one of said units to face in an opposite direction during the 15 operation of the hand operated means.

36. In an amusement device, the combination of a plurality of units, a course along which said units are adapted to travel, a plurality of hand operated means, means connected with said units to cause the same to travel along the course at a speed which is determined by the speed of operation of 20 said hand operated means, and automatic means for controlling the speed of any one of said units during the operation of the 25 hand operated means.

37. In an amusement device the combination of a unit, a course along which said unit is adapted to travel, a hand operated member for controlling the displacement of 35 said unit, and means interposed between said hand operated member and said unit to vary the speed of travel of said unit.

38. In an amusement device, the combination of a unit, a course along which said 40 unit is adapted to travel, hand operated means for controlling the displacement of said unit, and means responsive to increase speed of said member to cause a decrease in the speed of said unit.

39. In a device of the character described, a clutching device comprising a rotating member having a threaded aperture therein, and a rotating member provided with an external thread which is adapted to engage 45 with said threaded aperture in the other member to impart a longitudinal unclutching or clutching movement thereto.

40. In a device of the character described, a clutching device comprising a member rotating at constant speed which is provided 50 with a threaded aperture, a member rotating at variable speed, and a screw thread carried by said last mentioned member which is adapted to engage with the 55 threaded aperture of the constant speed member for imparting a longitudinal unclutching or clutching movement thereto.

when the speed of the variable speed member exceeds or is lower than a predetermined value.

65

41. In a device of the character described, a clutching device comprising a sliding sleeve, a member adapted to actuate said sleeve to effect the unclutching of two aligned shafts and means on said actuating 70 member for preventing relative angular displacement of said shafts until the lever has been moved to its extreme position.

42. In a device of the character described, a clutching device comprising an actuating 75 member which is capable of angular movement to unclutch two aligned shafts and means on said member for preventing relative movement of said unclutched shafts during the movement of said member from 80 one extreme angular position to the other.

43. In a device of the character described, two aligned shafts, a sliding sleeve embracing contiguous ends of said shafts, means for permanently securing said sleeve to one of 85 said shafts while allowing of relative movement, means for securing said sleeve to the other shaft, a cam operatively connected with said sleeve, a shaft on which said cam is mounted so as to be capable of lateral 90 movement, a spring controlled member for controlling said lateral movement and effecting connection between the cam and the shaft, a member for angularly displacing said cam and means carried on the cam for 95 preventing relative movement of the unclutched shafts during the movement of said cam from one extreme angular position to the other.

44. In a device of the character described, 100 two aligned shafts, a sliding sleeve embracing contiguous ends of said shafts, a spring for retaining said sleeve in the clutching position, a cam for displacing said sleeve to effect the unclutching of the shafts, a shaft 105 supporting said cam and passing through an enlarged aperture therein so as to allow relative movement between the cam and the supporting shaft, a spring controlled pin for connecting the cam and shaft and controlling the relative lateral movement thereof, and means carried by said cam for applying graduated pressure to the sleeve after the unclutching operation to prevent 110 relative angular displacement of the unclutched shafts.

In testimony whereof we affix our signatures in presence of two witnesses.

AXEL VALDEMAR CLORIUS.
ODIN THORVALD CLORIUS.
